**ELECTRICALLY OPERATED STARTING AID
FOR DIESEL ENGINES**

Matthew L. Kus, Sycamore, Ill., assignor to Turner Corporation, Sycamore, Ill., a corporation of Illinois
Filed July 13, 1962, Ser. No. 209,687
4 Claims. (Cl. 123—187.5)

This invention relates generally to automotive starting aids and more particularly relates to an improved electrically operated starting aid for diesel engines.

In accordance with the principles of the present invention, a so-called measured shot starting aid is provided for a diesel engine wherein the solenoid actuating motor is controlled by circuit means requiring the conjoint action and operation of an ignition switch and a push button switch and only when the engine is at temperatures below normal operating temperatures, thereby defeating any attempt by an operator to inject starting aid fluid into the intake manifold of the engine either while the vehicle is in motion or after the engine has been warmed to normal operating temperatures.

It is an object of the present invention, therefore, to provide an improved starting aid system for an automotive vehicle.

Yet another object of the present invention is to provide an improved control system for an electrically operated starting aid which has improved safety factors.

Yet another object of the present invention is to provide an improved control system for an electrically operated starting aid which prevents the operator from using the starting aid device while the engine is in normal operation or after the engine has attained normal operating temperatures.

Many other features, advantages and additional objects of the present invention will become manifest to those versed in the art upon making reference to the detailed description which follows and the accompanying sheets of drawings in which a preferred structural embodiment of a starting system and control system incorporating the principles of the present invention is shown by way of illustrative example.

On the drawings:

FIGURE 1 is a somewhat schematic view showing the components of the starting system and also showing various elements of an automotive internal combustion engine in association with the operative parts of the starting aid device of the present invention; and

FIGURE 2 is a view of the starting aid device with parts broken away and parts illustrated in section to illustrate additional details of construction.

As shown on the drawings:

The principles of the present invention are of general applicability to any starting aid system for an internal combustion engine. However, the illustrated form of the invention is particularly useful when applied to the starting system of a diesel engine since it is well recognized that diesel engines are somewhat difficult to start, particularly in subzero operating environments.

Thus, in FIGURE 1 there is shown schematically a mounting wall at 10 which can conveniently comprise the fire wall separating the engine compartment from another part of the vehicle.

At 11 there is shown an exhaust manifold forming part of the internal combustion engine or, in this instance, the exhaust manifold of the diesel engine and it will be understood that the hot gases of combustion discharged from the engine are exhausted through the manifold 11.

At 12 there is illustrated an intake manifold through which fuel is injected to the cylinders of the engine.

At 13 is illustrated the dashboard or control panel

2

which will be conveniently located for ready accessibility by the operator of the vehicle.

On the control panel or dashboard 13 there is provided an ignition switch 14 which is actuated by an ignition key 16 and which is used to control an electric circuit including a conduit wire shown at 17.

Also located on the control panel or dashboard 13 is a pushbutton switch 18 having a push button actuator 19 located in an accessible location for operation by the vehicle operator. The push button switch 18 is also used to control the same electric circuit and a conductor wire 20 is shown directly connected to the push button switch 18.

A heat plate is shown at 21 and includes a generally U-shaped member having a central bright portion 22 and offset legs 23 each terminating in a flanged foot 24 adapted to engage against the outer peripheral surface of the exhaust manifold 11.

Each foot portion 24 has an upturned toe 26 to better retain a strap clamp 27. Thus, each strap clamp 27 braces the exhaust manifold 11 and upon tightening of a corresponding fastener 28 will hold down the foot portion 24 in close conductive contact with the exhaust manifold 11.

The heat plate is made of material having good heat conductivity so that the bright portion 22 will readily partake of the temperature of the exhaust manifold 11 through the foot 24 and leg 23 and will quickly and accurately transmit to a thermally sensitive switch 30 a reliable indication of the operating temperature of the engine as reflected by the normal operating temperature of the exhaust manifold 11 during a running operation of the engine. The thermally sensitive switch 30 is interconnected into the electric circuit by the conductor wire 20 and by a conductor wire shown at 31.

A clamping assembly is readily connected to the fire wall 10 and such clamping assembly includes a bracket 32 retained by a screw fastener 33. A clamp loop 34 cooperates with a toggle handle 36 and a clamp strap 37 which operates to engage and tightly clamp a container or tank 38 in firm assembly with the fire wall 10. The container or tank 38 is of the type containing a supply of starting aid formulations. Any formulation exhibiting the characteristics of a sufficiently low boiling point to provide a combustible mixture at sub-zero temperatures can be used with the apparatus of the present invention.

The dispenser unit used in conjunction with the tank 38 is illustrated herein as comprising a so-called "measured shot" device. It should be understood that a so-called "continuous shot" device could also be used in accordance with the principles of this invention.

The conductor wires 17 and 31 are connected to energize an operating coil of a solenoid shown generally at 40 and which is used to actuate a measuring device connected to the tank 38, thereby to discharge a predetermined quantity of starting aid through an outlet 41 having a reducer 42 connected thereto and an elbow 43. The elbow 43 is connected to a length of tubing 44 which may include a helically wound portion 46 for convenience in shipping and adaptation to existing engines, thereby to provide a sufficient length of tubing to afford an expansion zone in which the starting aid liquid expands into the form of a gas, whereupon the combustible gas is discharged out of an orifice-forming means 47 situated at the center of the intake manifold 12.

To position the orifice-forming means 47, there is provided a fitting 48 threaded into a tapped opening 49 which can be readily and conveniently drilled in the intake manifold 12. The fitting 48 receives a compression ring 50 which is compressed against the outside of the tube 44 by a locking nut 51.

To facilitate mounting of the solenoid actuated measur-

ing device 40 on the fire wall 10, there is provided a mounting bracket 52 secured by a plurality of fasteners 53 on the fire wall 10. The bracket 52 may carry a dust cover 54 for use in capping the solenoid valve assembly when there is no container or tank 38 in assembly therewith.

Referring now to FIGURE 2, the container or tank 38 is shown as including an outlet fitting 56 in which is situated a tire valve 57 having an actuator stem 58. The fitting 56 is externally threaded as at 59, thereby to facilitate threaded assembly with a cylinder shown generally at 60. The cylinder 60 has an inlet end 61 and an outlet end 62 and forms the central part of the measuring device which is encircled by the solenoid 40. More specifically, the solenoid 40 has a coil 63 which is connected to the conductor wires 17 and 31. As shown in FIGURE 1, the bracket 53 is connected to ground via the frame of the automotive vehicle. The solenoid is encased within a housing 64. The coil 63 acts on an armature 66 which constitutes a plunger or piston including an actuating stem 67 adapted to engage and actuate the stem 58 of the tire valve 57.

The piston 66 further includes a first valve head 68 which extends radially outwardly and has one face engaging an O ring 69. The cylinder forms a shoulder 70, thereby confining the O ring 69 between the shoulder 70 and the valve head 68. Thus, when the coil 63 remains deenergized, the valve head 68 seals against the O ring 69 and against the shoulder 70.

The piston 66 also has connected thereto a washer 71 for bottoming a biasing spring 72, the other end of which is engaged against a shoulder 73 formed in the cylinder 60, thereby providing a normal continuous spring bias for loading the piston 66 in one direction.

A measuring chamber 74 is formed in the cylinder 60 between the shoulder 70 and a shoulder 76 spaced therefrom engageable with a second O ring 77 carried by a retainer 78 carried on the lower end of the piston 66.

In operation, when the coil 63 is energized, the piston 66 is moved upwardly. The actuating stem 67 engages the stem 58 of the tire valve 57 and the valve head 68 moves away from the O ring 69. The valve head formed by the retainer 78 and the O ring 77, in turn, engages against the shoulder 76 and seals the lower end of the measuring chamber 74. Thus, a quantity of the starting aid or fuel contained within the container or tank 38 is admitted through the passage prescribed by the cylinder 60 and within the limits prescribed by the size of the measuring chamber 74.

It will be apparent that no matter how long the operator continues holding down the push button 19, no more than a measured quantity of fuel enters the measuring chamber 74.

When the coil 63 is deenergized, the piston 66 moves downwardly and the valve head 68 seals against the O ring 69 which, in turn, seals against the shoulder 70 while the retainer 78 and O ring 77 move away from the shoulder 76 permitting the fluid to exit from the measuring chamber 74 through the outlet 41 and into the tubing 44.

By virtue of the spring bias exerted by the spring 72, even though there is a leak or if the tank valve 57 should stick, the upper section ahead of the measuring chamber 74 will be securely sealed.

The starting aid or fuel discharged into the tube 44 will expand in the expansion portion 46 and chamber 74 and will be delivered as a combustible gas mixture to the intake manifold 12. The procedure may be repeated as many times as is necessary to get the engine started. As soon as the engine does start and the hot gases of combustion pass through the exhaust manifold 11, the heat plate 21 will be elevated in temperature, thereby actuating thermally sensitive switch 30 and opening the circuit. Energization of the solenoid coil 63 is dependent upon the actuation of the push button switch 18 while the thermally

5

sensitive switch 30 is closed. The key switch 14, of course, is a part of the vehicle and is also incorporated into the circuiting as an added control to insure operation of the device only by an authorized operator during an engine starting operation. Accordingly, it will be apparent that the operator will be prevented from using the starting aid fuel while the vehicle is in normal operation or after the engine has been warmed to a normal operating temperature.

The device of the present invention can be readily installed on existing equipment merely by fastening the brackets 32 and 52 on the fire wall. A mounting hole is easily formed in the control panel or dashboard 13 for accommodating the dashboard push button switch and the thermostat switch is readily connected to the exhaust manifold 11 by the clamps 27, 28.

The inlet manifold 12 is equipped for operation by the addition of the fitting 48 and the conductor wires 17, 20, 31 are readily interconnected with the electric circuitry of the vehicle by the use of quick connect wire connectors.

Although minor modifications might be suggested by those versed in the art, it should be understood that I wish to embody within the scope of the patent warranted hereon all such modifications as reasonably and properly come within the scope of my contribution to the art.

I claim as my invention:

1. In a starting system for an internal combustion engine having an intake manifold, control circuit means for a starting aid device including electrically operated actuating means for selectively injecting a shot of starting aid into the intake manifold of the engine, a normally open control push button switch in said circuit means, and a normally closed thermally sensitive switch in said circuit means having a thermal element connected to the exhaust manifold of the engine to open the thermally sensitive switch when the exhaust manifold reaches engine operating temperatures, whereby said starting aid actuating means can be actuated only upon operation of the control push button switch when said thermally sensitive switch is closed, said actuating means comprising a solenoid motor having an armature plunger comprising a piston movable axially from a first to a second position upon energization of said coil, a tank of starting aid liquid, a cylinder in which said piston moves including a coupling connection at one end for attachment to said tank of liquid, said cylinder including shoulders at opposite ends thereof prescribing therebetween a measuring chamber, said plunger having spaced O rings each engageable with one of said shoulders when said plunger is at either said first or at said second position, said tank having a safety valve engaged by said plunger, said cylinder and said plunger operable to admit a measured quantity of liquid from said tank into said measuring chamber, and conduit means connecting said measuring chamber to the intake manifold of the engine.

2. A starting aid device comprising a cylinder having an inlet at one end, an outlet at the other end and a measuring chamber therebetween, a piston in said cylinder having first and second valve heads at opposite sides of said measuring chamber, said piston comprising the armature of a solenoid, a solenoid coil surrounding said cylinder and operable

upon energization thereof to move said piston from a first position to a second position, said piston having at one end thereof an actuator portion for engaging and opening the valve of a starting aid container connected to said inlet, whereby a measured quantity of starting aid is delivered into said measuring chamber, conduit means connected to said outlet for directing the contents of the measuring chamber to the intake manifold of an internal combustion engine having an exhaust manifold, and control means for said solenoid including a push button switch, and a thermal switch connected to the engine exhaust manifold, said control means effective to operate said starting aid only upon the actuation of said push button switch when the engine manifold is at a reduced temperature.

3. In a starting system of an internal combustion engine having an exhaust manifold and an intake manifold, an electrically operated starting aid feeding device including means for selectively feeding a starting aid into the intake manifold, and control means for said electrically operated device including a thermally operated switch, a heat plate made of good thermally conductive material and carrying said switch,

said heat plate comprising a bight portion mounting said switch, leg portions offset from said bight portion, each said leg portion having an offset foot portion for engaging the exhaust manifold, each said foot portion having an offset toe portion for retaining a clamp, whereby the device may be clamped to the exhaust manifold of the internal combustion engine, thereby to conduct thermal energy there-

from for actuating said thermally operated switch, to prevent operation of the starting aid device when the engine is at operating temperatures.

5 4. In a starting system for an internal combustion engine having exhaust and intake manifolds, a starting means including a starting aid device, said starting aid device having starting aid injection means connected to the intake manifold for selectively injecting a shot of starting aid into the engine, control circuit means for the starting aid device including electrically operated actuating means for regulating the selective flow of starting aid electrically, a normally open control push button switch in said circuit means, and a normally closed thermally sensitive switch in said circuit means having a thermal element connected to the exhaust manifold of the engine to open the thermally sensitive switch when the exhaust manifold reaches engine operating temperatures, whereby said starting aid actuating means can be actuated only upon operation of the control push button switch when said thermally sensitive switch is closed.
